In Germany July 15, 1933

2 Claims. (Cl. 101—282)

This invention relates to a cylinder machine provided with a two-revolution impression cylinder and front delivery of the printed sheets.

The invention aims at avoiding the drawbacks connected with the known types of stop-cylinder and two-revolution machines and of uniting all the advantageous features of these two kinds of machines in one machine. To attain its object the invention provides that the second revolution of the impression cylinder is effected independently of the length of travel of the carriage causing the first revolution of the impression cylinder by means of a special additional member, such as a specially driven toothed segment or a horizontally operating rack.

In the cylinder machine according to the invention the sheets to be printed are fed while the impression cylinder is in a position of rest whereby absolutely accurate feeding is insured and correct register is attained in color work. The machine according to the invention requires little space, less even than a stop-cylinder machine, is available at a low initial price, simple to operate and provided with front delivery of the printed sheet to prevent slurring. The machine parts are not subjected to abnormal stresses and wear.

By way of example, the invention is illustrated in the accompanying drawings, in which Figure 1 is a side view of the machine; and Fig. 2, a side view of the machine in another position.

Referring to the drawings, 1 is the main drive which actuates the crank shaft 2. The carriage wheel 3 is moved to and fro by the connecting rod 4 and the transmission levers 5, 6, so that the rod 4 has a shorter path to travel and the gearing of the crank shaft 2 will be correspondingly lower whereby it becomes possible to make the machine shorter and lower.

40 The driving lever for the carriage wheel operates in an almost horizontal position, so that the type bed is not subjected to shocks.

The carriage wheel 3 rotates between the racks 8 and 9, the rack 8 being stationary whereas 45 the rack 9 is secured below the carriage 10 to which the rack 11 is attached. The impression cylinder 12 is positively rotated during the advance of the carriage 10, owing to the engagement of the rack 11 with the toothed rim 13 arranged on it. Independently of this rotation, a second rotation of the cylinder is effected by separate means comprising a toothed member which 50 may be a toothed segment 14 or a horizontally operating rack or the like. The toothed segment 55 14 disposed on the fulcrum 15 is rotated by means

of the lever 16 and the eccentrics 17 and 18. By means of the eccentric 19 and the roller lever 20 fixed on the pivot 21 the toothed segment 14 arranged on the fulcrum 15 is raised and lowered and brought into and out of engagement with the gear 22 firmly connected with the impression cylinder 12 which is thus rotated a second time.

The process of printing a sheet is not composed of two operating periods or steps as in stop-cylinder machines, but divided into three steps 10 which are equally spaced as to time. The first step consists in guiding the sheet by hand or suitable automatic means to the cylinder and causing the grippers to hold it while the impression cylinder stops. At the beginning of the second 15 step the toothed segment 14 starts at a gradually increasing speed the rotation of the cylinder 12 (Fig. 1). When the latter, after a short travel, has attained normal carriage speed, the rack of the advancing carriage engages the toothed rim 20 of the cylinder. For a short distance, the toothed segment 14 and the rack 11 of the carriage 10 will jointly rotate the cylinder 12. After the rack 11 of the carriage 10 has, so to speak, taken over the cylinder 12, the toothed segment 25 14 will be lowered so as to become unmeshed and the carriage 10 will continue to move the cylinder 12 until a full revolution is effected during which the sheet is printed.

In the meantime, the toothed segment 14, by 30 means of the lever and eccentric transmission as described and as shown in Fig. 2, has been placed in opposite position by being moved under and past the toothed rim 22 of the impression cylinder. Shortly before the first revolution of 35 the impression cylinder 12 has been completed, the toothed segment 14 engages again the toothed rim 22 and cooperates for a short time with the rack 11 of the carriage 10 at the same speed as the latter. During this movement the 40 toothed segment 14 takes over the impression cylinder 12 and acts alone in rotating it to the extent of a second full revolution, whereas the rack 11 of the carriage 10 has become disengaged from the toothed rim 13, reversed in end 45 position and passed under the cylinder at 23 where the teeth of the rim 13 are removed at the completion of the second revolution, so that the rack 11 of the carriage 10 cannot collide with the toothed rim 13 of the impression cylinder 50 12. The carriage 10 has thus returned to initial position (Fig. 1).

During completion of the second revolution of the impression cylinder 12 a slow retarded motion has been imparted to the toothed segment 14 55

by the corresponding eccentric to insure soft stopping of the cylinder in contrast with stop-cylinder machines in which it is suddenly held up by the cylinder brake or catch.

5 5 **5** Shortly before the first revolution of the cylinder 12 has been completed, the printed sheet is passed with the printed side up over the delivery roller 24 to the pile table 61, whereby an object hitherto reserved to the two-revolution machines 10 has been attained also.

10 In view of this motion and arrangement of the drive for the impression cylinder it is necessary to dispose the inking apparatus behind the impression cylinder, i. e., under the feed table.

15 I claim:—

1. A drive in cylinder machines, comprising a carriage, a rack for said carriage, an impression cylinder, a multilated toothed rim on the circumference of said cylinder, said rim being engaged 20 by said rack to bring about a revolution of the impression cylinder, a second toothed rim on said impression cylinder, a movably disposed toothed segment, means comprising eccentrics and a roller lever for lifting and lowering said toothed 25 segment and additional eccentrics and a lever for imparting to said toothed segment a slowly starting and stopping oscillatory motion and bringing it into engagement with the second toothed rim on the impression cylinder to alternately rotate the cylinder with said carriage,

whereupon said toothed segment by said means initiates slow rotation of the impression cylinder and the rack engages the other toothed rim on the impression cylinder and said toothed segment by said means is lifted out of the second rim and the carriage alone completes the first rotation of the impression cylinder and before completion of the first revolution of the impression cylinder the toothed segment by said means engages again the second toothed rim and causes 10 the second revolution of the impression cylinder, said means regarding the motion of the toothed segment to gradually stop the impression cylinder after the second revolution, said carriage and rack returning to initial position under and 15 past the mutilated portion of said first toothed rim.

2. A cylinder machine with front delivery of sheets, comprising an impression cylinder having two toothed rims at its circumference, a reciprocating carriage, a rack for said carriage, a toothed gear member and means for alternately raising and lowering said toothed member and imparting oscillatory motion thereto to cause said rack and toothed member alternately to 20 engage the toothed rims of the impression cylinder, the to and fro motion of the carriage corresponding to three circumferences of the impression cylinder at two revolutions thereof. 25
